UNITED STATES PATENT OFFICE.

EDWARD COVERLY NEWCOMB, OF NORTH SCITUATE, MASSACHUSETTS, ASSIGNOR
TO NEWCOME CARBURETER COMPANY, A CORPORATION OF NEW YORK.

CARBURETER.

1,359,828.

Specification of Letters Patent. Patented Nov. 23, 1920.

Application filed October 25, 1915. Serial No. 57,634.

To all whom it may concern:

Be it known that I, EDWARD COVERLY NEWCOMB, a citizen of the United States, and a resident of North Scituate, Plymouth county, Commonwealth of Massachusetts, have invented certain new and useful Improvements in Carbureters, of which the following is a specification.

My invention relates to carbureters such as are used for supplying a mixture of fuel and air to internal combustion engines and is of the same general type as shown in my previous Patent No. 1,010,066, of November 28, 1911.

15 The object of my present invention is to provide means to limit the accumulation of liquid fuel in the carbureter due to condensation in the carbureting chamber, at the same time leaving a sufficient amount of 20 liquid fuel to insure proper carburation when sudden increased demands for mixture are made upon the carbureter.

A further object of my invention is to return to the mixture in a finely atomized 25 and aerated form the excess of the liquid fuel which condenses and accumulates in the mixing chamber.

These and other objects of my invention are more fully explained in the following 30 description, the essential features of which are pointed out in the specification and in the appended claims.

In the drawings which are referred to herein and form a part hereof is illustrated 35 one embodiment of my invention, the same serving in connection with the description to explain the principles thereof.

Figure 1 of the accompanying drawing 40 is a vertical section of my carbureter, partly in section.

Fig. 2 is a section of my residual fuel pulverizer.

Figs. 3 and 4 show its application to 45 points in the manifold designed to correct faulty distribution of the mixture.

Similar characters refer to similar parts throughout the accompanying drawings.

Referring now to the drawings, my carbureter consists of the casing 1, having at 50 its top an outlet for the mixture in the form of a flange-neck tube 2, adapted to be connected to the manifold of the engine. This outlet is controlled by a butterfly throttle valve 3. The casing 1 is open at its lower 55 end, and within this casing is secured a tu-

bular member 6 the opening in the upper end of which is closed by a plug 4. This member 6 is open at its lower end and is provided in its side walls with a multiplicity of narrow elongated air ports 7, which discharge into the carbureting chamber 7a. These ports are normally closed by the piston valve 8, which is adapted to be raised by the suction of the engine so as to uncover the ports 7 more or less in accordance with the quantity of mixture demanded by the engine, the fit of the piston air valve being such that the air may be gradually withdrawn from the chamber above said piston valve. The weight of the piston valve 8 70 also establishes the vacuum under which the carbureter normally operates. In order to properly control the movements of the piston valve 8 and prevent undue fluttering, it is provided with an upwardly extending 75 closed tubular portion 9 fitted to the interior air port member 6, while the top of the latter member is closed. The fit of the piston in the member 6 being such that the air will be gradually drawn from the space 80 above the piston and cause the piston to rise. In order to permit the piston to fall promptly and prevent an undue lowering of the vacuum when the demand for fuel is suddenly decreased, I provide a ball check 85 10 in the top wall thereof. The plug 11, cross-shaped in cross-section so as to provide passages 11a, is driven into the upper end of the chamber 5, in which the ball 11b rests to retain the ball in the chamber. The 90 fuel is supplied through a pipe 12 to a float feed chamber 13, where it is maintained at a predetermined level by the float 14 operating the valve 15. From the float feed chamber 13 the liquid fuel is supplied 95 through the passage 16 to the jet 17, the port of which is controlled by the needle valve 18, which is secured to the piston valve 8, the needle valve being so tapered that the proper proportion of fuel will be discharged 100 from the jet 17 into the chamber 8a of the piston 8 to properly carburet the air entering the carbureting chamber through the air ports 7. The fuel which is thus admitted to the chamber 8a of the piston valve 8 is 105 discharged into the carbureting chamber through the ports 8a, where it is pulverized by the streams of rapidly inrushing air entering through the ports 7. In the base of the casing 1, I form an annular capillary 110

chamber 19, and at one point I enlarge this chamber to form a sump or well 20. It is apparent that all liquid fuel which condenses in the shell 1, which forms the carbureting chamber, will tend to accumulate in the annular chamber 19 and the sump 20. In order to limit the quantity of fuel which may be accumulated, I provide a tube 21 extending downward through the shell 1 to a point directly above the sump 20. The upper end of this tube 21 is secured, preferably by brazing, in a ring 22, which is provided with an annular channel 23 and is secured to the neck 28 of the carburetor by means of the gland-screw 24. The gland-screw 24 is perforated axially to provide passages 25 and 26, the passage 25 being of larger bore than the passage 26. The gland-screw 24 is also provided with a lateral passage 27 communicating with the passage 25 and with the chamber 23. The operation of my device is as follows:

When the throttle valve is nearly closed and the engine to which the carburetor is connected is running at slow speed the travel of the mixture is so slow that the liquid fuel tends to condense and accumulate in the base of the carbureting chamber in disturbing quantities. This tendency is increased where fuels of low volatility, such as are now commonly used, are supplied to the carburetor, and it is mainly the heavier fractions of such fuel which so condense. It is, however, desirable that a limited accumulation should be provided for in a carburetor of the type shown, because when the engine has been running slowly with the throttle nearly closed, if the throttle is suddenly opened, there is a marked tendency for the fuel to be precipitated in the manifold because of the low rate of travel of the mixture and the reduced vacuum in the manifold resulting from sudden opening of the throttle valve. Under these conditions, retardation of the lift of the piston valve 8 results in a sudden and considerable rise in the vacuum in the carbureting chamber which greatly accelerates the velocity of the air entering the mixing chamber through the ports 7 causing the air to pick up and pulverize the fuel accumulated in the chamber 19, thereby restoring to the mixture its normal proportion of fuel properly pulverized. If, however, too great a quantity of fuel is allowed to accumulate, the mixture under the conditions stated becomes over-rich. When the throttle valve is partially closed the vacuum existing between the throttle valve and the engine is always considerably higher than the vacuum existing in the carbureting chamber when the carburetor is in operation, with the result that all but a predetermined quantity of the liquid fuel which accumulates in the chamber 19 and the sump 20 is drawn upward through the tube 21 into the cham-

ber 23, and thence through the passage 27 into the passage 25 where it is met by air rushing into the passage 25 through the passage 26, from which point it passes through the passage 25 into the neck 28 of the carburetor in a highly atomized condition. The passage 26 having a bore about one-half the diameter of the bore of the passage 25, the air admitted through the passage 26 rushes at high velocity across the passage 27 and into and through the passage 25, the high vacuum beyond the throttle imparting to it sufficient velocity to properly pulverize even the heavy fractions of the liquid fuel used.

The elevation of the lower end of the tube 21 above the bottom of the sump 20 determines the amount of liquid fuel which it is allowed to accumulate in the sump 20 and the annular chamber 19.

I have found that in many of the types of manifolds in use that there is a marked tendency to distribute the mixture unevenly to the various cylinders of the motor to which the carburetor is connected, and to supply a richer mixture to certain cylinders than to the other cylinders. This condition can be corrected by so disposing the passage 25 that the mixture entering through the passage 25 will correct the distribution of the mixture through the manifold.

In Fig. 3, I have shown the pipe 21 divided at 29 into two branches, 30 and 31, each of which is supplied with atomizers 32 and 33 similar to the atomizers in Fig. 2.

It will thus be seen that my invention will carry the heavy fractions of the liquid fuel, which are the fractions which tend to accumulate in the chamber 19 and the sump 20 to points in the manifold near enough to the engine cylinders so that they will be conveyed into the cylinders before they have an opportunity to condense. As the atomizer which acts upon these fractions operates under a comparatively high vacuum, this fuel is so finely pulverized and so aerated that when delivered to the manifold at points near the engine it has little tendency to condense.

In Fig. 4, I have shown the atomizer so directed into the manifold as to correct the faulty distribution of mixture, due to the unsymmetrical shape of the manifold pipe.

Having described my invention, I claim:

1. A carburetor comprising in combination a carbureting chamber, a sump in the carbureting chamber in the path of the entering air in which a predetermined quantity of the liquid fuel which condenses in the carbureting chamber is collected and normally retained, and means for atomizing and adding the fuel so stored in said sump to the mixture when a sudden increased demand for mixture is made upon the carburetor.

2. A carburetor comprising in combina-

tion, a carbureting chamber, air and fuel ports discharging into said carbureting chamber, a reservoir in the carbureting chamber in the path of the entering air 5 adapted to collect and normally contain a predetermined quantity of the liquid fuel which condenses in the carbureting chamber, and means for delivering the fuel so collected and normally retained to the mixture in a finely atomized condition when a sudden demand for an increased quantity of mixture is made upon the carbureter.

3. A carbureter comprising in combination, a carbureting chamber, air and fuel ports discharging into said carbureting chamber, a reservoir in the carbureting chamber in the path of the entering air in which the liquid fuel which condenses in the carbureting chamber is collected, means 20 for limiting the quantity of fuel which may be retained in said reservoir, and means for delivering to the mixture in a finely atomized condition the fuel retained in said reservoir when a sudden demand for an increased quantity of the mixture is made upon the carbureter.

4. A carbureter comprising in combination a carbureting chamber, air and fuel ports discharging into said carbureting chamber, a suction controlled air valve 30 adapted to cover and uncover the air ports, a reservoir located in said carbureting chamber in the path of the air entering the carbureting chamber through the air ports in

which a predetermined quantity of the liquid fuel which condenses in the carbureting chamber is collected and normally retained, and means for checking the opening movement of said air valve constituting means for causing the air entering through said air 40 ports to pick up and pulverize the liquid fuel normally retained in said reservoir when a sudden demand is made upon the carbureter for an increased quantity of mixture. 45

5. A carbureter comprising in combination a carbureting chamber, air and fuel ports, discharging into the carbureting chamber, a suction controlled valve adapted to cover and uncover said air ports a capillary reservoir in the base of said carbureting chamber and located in the path of the air entering said carbureting chamber through said air ports and adjacent to said air ports into which the fuel which condenses in the 55 carbureting chamber is collected, a sump communicating with said reservoir, a pipe, the upper end of which is in open communication with the neck of the carbureter beyond the throttle valve and the lower end 60 of which pipe is adjacent to said sump.

Signed at New York city, in the county of New York, and State of New York, this 11th day of October, 1915.

EDWARD COVERLY NEWCOMB.
